No. 688,252.

Patented Dec. 3, 1901.

J. KELLER.

PNEUMATIC RAMMER.

(Application filed July 10, 1901.)

(No Model.)

UNITED STATES PATENT OFFICE.

JULIUS KELLER, OF PHILADELPHIA, PENNSYLVANIA, ASSIGNOR TO
PHILADELPHIA PNEUMATIC TOOL COMPANY, A CORPORATION
OF NEW JERSEY.

PNEUMATIC RAMMER.

SPECIFICATION forming part of Letters Patent No. 688,252, dated December 3, 1901.

Application filed July 10, 1901. Serial No. 67,711. (No model.)

To all whom it may concern:

Be it known that I, JULIUS KELLER, a citizen of the United States, residing in the city and county of Philadelphia, State of Pennsylvania, have invented a new and useful Improvement in Pneumatic Rammers, of which the following is a specification.

My invention consists of an improved construction of a pneumatic rammer having a piston therein provided with an integral piston rod or extension and means for preventing said rod and piston from turning in the cylinder of said rammer, the interior of said rammer being also provided with means normally out of contact with the piston for retaining the piston at or near the rear extremity of the cylinder when not in use.

It also consists in providing the cylinder of the rammer on one side with a grasping-handle having a thumb, finger, or hand operated lever adapted to control the inlet of the motive fluid, which latter passes through the wall of the cylinder and after being utilized to reciprocate the piston and actuate the distribution-valve passes outwardly through a suitable portion of a second grasping-handle attached to said cylinder opposite to said first-mentioned handle.

It also consists of the novel combination of a pneumatic-tool cylinder or casing, extensions projecting therefrom, and grasping-handles mounted on said extensions and projecting rearwardly therefrom in substantial alignment with the axis of said casing.

It also consists of a novel arrangement and location of a hollow differential or other distribution-valve employed and in the novel arrangement of coacting ports common to said piston and valve.

It also consists of a novel construction of a sectional valve-box and of a novel arrangement of the ports and passages therein.

It further consists of novel details of construction, all as will be hereinafter set forth, and particularly pointed out in the claims.

Figure 1 represents a longitudinal sectional view of a pneumatic rammer embodying my invention, certain of the parts being shown in elevation. Fig. 2 represents a sectional view of the rammer seen in Fig. 1, the sec-

tion being taken on a different plane from that seen in Fig. 1. Fig. 3 represents a perspective view of the spring-clamp or piston-retaining device employed. Fig. 4 represents, on a reduced scale, a perspective view of Fig. 1. Fig. 5 represents a sectional view showing the location of the exhaust-ports.

Similar characters of reference indicate corresponding parts in the figures.

Referring to the drawings, 1 designates my pneumatic rammer, having the cylinder 2, within which reciprocates the piston 3, which is preferably a solid piece of metal having integral therewith the hexagonal or other polygonal shaped rod or extension 4, which extends through the front end 5 of said cylinder and is tapered at its extremity to hold the stamper 6.

7 designates a gland having a polygonal opening therethrough corresponding to the contour of the extension 4, the latter passing through the packing 8, which is held in position by said gland, while the latter is retained in position by the jam-nut 9.

10 designates a recess in the rear portion of the cylinder 2 and slightly larger than the bore of said cylinder, wherein is contained the spring-clamp or piston-retainer 11, the latter consisting of a split ring, into which the piston is adapted to be pushed when at rest, whereby said clamp will hug said piston and retain and sustain the latter when not in use in its uppermost position.

12 designates the differential distribution-valve, which is structurally similar to the distribution-valve described and claimed in my prior patent, No. 647,415, granted to me April 10, 1900, although the location of the ports and passages herein and their coaction with the distribution-valve in my present invention differs materially from any prior patents granted to me, as will be hereinafter explained. The valve 12 is contained within the valve-box, consisting of the front and rear sections 13 and 14, respectively, which are held in position by the valve-box cover 15, which is in threaded engagement at its forward portion with the contiguous end of the cylinder 2, said valve-box cover being locked in position by the jam-nut 16.

17 designates an oiling device, which can

be located in either of the positions seen in Fig. 1 or Fig. 2, in which latter figure I have shown the cylinder as provided with a single handle 18, having the inlet-passage 19, into which the motive fluid is conducted past the throttle-valve 20, which is located in the bushing 21 and held in position by the latch 22, said throttle-valve being held in position by the spring 23 and being operated by the lever 24. In some instances it will be found to be necessary or expedient to provide the cylinder 2 with two handles, as seen in Fig. 1, wherein 25 designates the inlet-handle, which is constructed substantially as seen in Fig. 2, and 26 designates the exhaust-handle, through the lower portion of which the exhaust passes to the atmosphere through the passage 27.

The motive fluid passes to the interior of the hollow distribution-valve 12 either through the passage 19, as seen in Fig. 2, or else through the inlet-passage 28, when the construction seen in Fig. 1 is employed, the motive fluid entering the valve-box through the port 29 in each instance. It will be noted that the distribution-valve is hollow and has fluid-pressure constantly acting on the interior thereof, and when the parts are in the position seen in Fig. 1 the piston 3 is near or at the end of its backward stroke, and the port 30 is open to admit the pressure (which has driven said piston backward or to the right) into the passage 31 and thence to the port 32, (best seen in Fig. 2,) at which point the pressure acts on the large pressure area 33 of the valve 12 and moves the latter into the position seen in Fig. 1. The port 34 is now connected through the groove 35 on the outside of the valve 12 with the exhaust-port 36, and the pressure from the front end of the piston will exhaust through the port 37, passage 38, port 34, past groove 35 to port 36, to the passage 27, (in Fig. 1) to the atmosphere, it being understood in the construction seen in Fig. 2 the exhaust passes from the port 36 through the port 39 to the atmosphere. The piston 3 is driven forwardly or to the left of the position seen in Fig. 1 when the valve 12 is in the position seen therein by the admission of motive fluid through the interior of the valve to the port 40 and passage 41 to the rear or right-hand end of said piston.

42 designates a very small auxiliary live-air port, which connects the main live-air port with the large pressure area 33 of the valve 12, so that it will be seen that when live-fluid pressure enters the port 40 and passage 41 to drive the piston 3 forwardly live-air pressure at the same time will enter said auxiliary port 42 and hold the valve 12 in the position seen in Fig. 1 until said piston in its forward stroke opens port 43 on passage 31 and also exhaust-port 44, which latter is substantially in line with said port 43. The pressure from the large pressure area 33 of the valve 12 is now released, and the latter

through the constant pressure on its small pressure area 45 is forced forwardly to the position seen in Fig. 2, thus opening the port 46, which is also connected with the passage 41 for exhaust, as best shown in Fig. 2. The piston is returned from the position seen in Fig. 2 to the position seen in Fig. 1 by the admission of live air through the port 34, passage 38, and port 37. The exhaust from the back end of the cylinder takes place through the passage 41, port 46, and passages 36 and 27 in the construction seen in Fig. 1, while in the construction seen in Fig. 2, where the handle is at the end of the cylinder, the air will exhaust through the passage 41, port 46, port 36, and main exhaust 39.

It will be apparent that slight changes may be made in the location and arrangement of the ports which coact with the piston and distribution-valve without departing from the spirit of my invention, and I reserve to myself the right to make all such modifications as fall within the scope thereof.

The stamper 6 can be of any suitable shape or contour and can be attached to the rod or extension 4 by any convenient means, and in order that said stamper may be in absolute control of the operator said piston-rod, on which the stamper is fastened, is made so as not to turn in the cylinder, said rod being shown in the present instance as of hexagonal shape in cross-section, although any other polygonal shape may be employed if desired.

I desire to especially emphasize the function of the spring-clamp or piston-retainer 11 in the rear end of the cylinder 2, since when the tool is not in operation the piston can be pushed all the way back into said clamp and will be held there until air is again applied or admitted to the piston. By this expedient the rod or extension 4, which is ordinarily about twelve inches long, is contained when not in use for the greater part of the length within its cylinder and is thus prevented from injury, whereas without the piston-retaining device the weight of the stamper and piston would tend to move the same outwardly, and the rod 4 would be exposed to injury and be liable to be damaged, as is evident. So far as I am aware I am the first to employ any device within the rear portion of a piston-cylinder in tools of this character for mechanically or otherwise retaining a piston in substantially the manner described within the rear extremity of its piston-chamber when the supply of motive fluid is cut off from the cylinder or when the tool is not in use, and my claims to this feature are therefore to be regarded as of corresponding scope.

For small-sized rammers the construction seen in Fig. 2 is preferable, where but a single handle is employed; but for the larger size of rammers, which are of such weight that they must be operated with two hands, the construction seen in Fig. 1 is preferable, the operator holding the tool with one hand

on the inlet-handle and the other on the exhaust-handle, whereby the tool can be readily manipulated.

I desire to emphasize the peculiar advantages attained by the novel assemblage in a single structure of the means for preventing the improper rotation of the piston, extension, and stamper, which I have arranged in coöperative relation to the device for retaining these parts when not in use within the cylinder, the coöperation of the means for preventing rotation of the piston, extension, and stamper with the pair of grasping-handles being also apparent, since, as is well known to those skilled in this art, the stamper must be manipulated so as to be applied during the ramming of the sand at the particular points in the foundry desired, and in order to enable the workman to handle the rammer with the desired facility it is necessary that a plurality of handles arranged substantially as shown be provided for this purpose, as is evident.

I desire to lay especial emphasis on the advantages of my invention, since before the piston 3 reaches its extreme left-hand position the valve will move in the same direction, and when the blow is delivered the valve is on the left-hand side, the blow instead of rebounding the valve from its seat tending to hold said valve more firmly seated, since the momentum or slight forward movement imparted to the tool-cylinder when said blow is struck must simultaneously impart a slight forward movement to the valve, since the latter and said piston move in the same direction, all the ports being open at the right time, and the regular and uniform movement of the valve, and consequently of the piston, is unobstructed, whereby jumping, jarring, and other objectionable features of pneumatic tools now in use are practically overcome.

It will be apparent that slight changes may be made by those skilled in the art which will come within the scope of my invention, and I do not therefore desire to be limited in every instance to the exact construction herein shown and described.

Having thus described my invention, what I claim as new, and desire to secure by Letters Patent, is—

1. In a pneumatic tool, a cylinder, a piston adapted to reciprocate within said cylinder and means within said cylinder and normally out of contact with said piston for retaining the latter when not in use at or near the rear end of said cylinder.

2. In a pneumatic tool, a cylinder, a piston adapted to reciprocate within said cylinder and means within said cylinder near the rear end thereof for retaining said piston when not in use at or near the rear end of said cylinder, said means being normally out of contact with said piston.

3. In a pneumatic rammer, a cylinder, a piston adapted to reciprocate within said cylinder and a spring-clamp within said cylinder

and adapted to engage said piston and retain the latter when not in use near the rear end of said cylinder.

7c

4. In a pneumatic rammer, a cylinder, a piston adapted to reciprocate within said cylinder, a polygonal extension integral with said piston, a polygonal opening in front of said cylinder through which said extension passes, packing contained within the front end of said cylinder, a gland also seated within said cylinder, said gland and packing having openings therethrough, corresponding to the contour of said extension, and means for locking said gland in position.

75

5. In a pneumatic rammer, a cylinder, a piston adapted to reciprocate within said cylinder, an extension integral with said piston, and a stamper attached to said extension in combination with means within said cylinder for retaining said piston when not in use near the rear end of said cylinder.

85

6. In a pneumatic rammer, a cylinder, a piston therein, a polygonal extension integral with said piston, a polygonal opening in the forward end of said cylinder, packing contained within said cylinder through which said extension passes, a gland secured against said packing, a polygonal opening in said gland, through which said extension passes, and a jam-nut for holding said gland in position.

90

7. In a pneumatic rammer, a cylinder, a piston thereon, a polygonal extension integral with said piston, a polygonal opening in the forward end of said cylinder, packing contained within said cylinder through which said extension passes, a gland secured against said packing, a polygonal opening in said gland, through which said extension passes, and a jam-nut for holding said gland in position, in combination with a stamper attached to said extension.

95

8. In a pneumatic rammer, a cylinder, a piston thereon, a polygonal extension integral with said piston, a polygonal opening in the forward end of said cylinder, packing through which said extension passes, a gland secured against said packing, a polygonal opening in said gland, through which said extension passes, and a jam-nut for holding said gland in position.

100

9. In a pneumatic tool, a cylinder, a piston therein, and a spring-clamp within said cylinder adapted to engage and retain said piston when not in use in the desired position.

105

10. In a pneumatic tool, a cylinder, a piston therein, an extension integral with said piston, a stamper on said extension, and means for retaining said piston near the rear extremity of said cylinder when not in use, whereby said extension is contained for the greater part of its length within its cylinder and thus prevented from injury.

110

11. In a pneumatic tool, a cylinder, a piston therein, a distribution-valve for said piston, means controlled by said piston for actuating said valve, and an auxiliary port open to live

115

- air after the movement of said valve has been effected by said piston, whereby an additional supply of live air is admitted to said valve to retain the latter in the desired position.
- 5 12. In a pneumatic tool, a cylinder, a piston therein, a differential distribution-valve for said piston, the smaller area of said valve being constantly exposed to fluid-pressure, and the larger area of said valve being intermittently exposed to fluid-pressure, a valve-box for said valve and a port in said valve-box for admitting live-air pressure to the larger area of said valve, after the latter has moved to admit live air to said piston,
- 15 13. In a pneumatic tool, a cylinder, a valve for controlling ports common thereto and to a piston, said valve consisting of a hollow shell or cylinder having its interior surface always open to fluid-pressure, said valve being located exteriorly to said piston in alignment therewith and adapted to move in the same direction as said piston, a sectional valve-box, and a passage controlled by said piston and opened by the latter to admit motive fluid to
- 25 the large pressure area of the valve to move the latter backwardly or away from said piston, said valve being moved forwardly by the constantly-acting pressure upon its smaller area.
- 30 14. In a pneumatic tool, a cylinder, a valve for controlling ports common thereto and to a piston, said valve consisting of a hollow shell or cylinder having its interior surface always open to fluid-pressure, said valve being located exteriorly to said piston in alignment therewith and adapted to move in the same direction as said piston, a sectional valve-box, and a passage controlled by said piston and opened by the latter to admit motive fluid to
- 35 the large pressure area of the valve to move the latter backwardly or away from said piston, said valve being moved forwardly by the constantly-acting pressure upon its smaller area, in combination with a port in said valve-box, opened by said valve after the latter has
- 40 been moved by pressure upon its larger differential area, whereby an auxiliary supply of live air is admitted to the larger pressure area of said valve.
- 45 15. In a pneumatic tool, a cylinder, a piston therein, a valve-box, a differential valve therein, a port for admitting motive fluid to move said valve in one direction by air-pressure upon its smaller differential area, a port for permitting said valve to be moved in the opposite direction by intermittent air-pressure upon its larger area, and an auxiliary port in said valve-box for admitting an auxiliary supply of live air to the larger area of said
- 55 valve, after the latter has been initially moved by said intermittent pressure.
- 60 16. In a pneumatic tool, a cylinder, a piston therein, a sectional valve-box, a hollow differential distribution-valve therein, ports for permitting motive fluid to move said valve in one direction by constant live-air pressure upon its smaller differential area, ports for

permitting said valve to be moved in the opposite direction by intermittent air-pressure upon its larger area, and an auxiliary port in said valve-box for admitting an auxiliary supply of live air to the larger area of said valve after the latter has been initially moved by said intermittent pressure.

17. In a pneumatic tool, a cylinder, a piston therein, a sectional valve-box, a valve-box cover inclosing said valve-box, and holding the latter against said cylinder, a valve in said valve-box, handles attached to opposite sides of said cylinder, an inlet-passage extending through one of said handles and discharging into a passage forming a continuation thereof and extending longitudinally of said cylinder, an inlet-passage in said box in communication with said last-mentioned passage, an exhaust-passage in said box and communicating with an exhaust-passage in said cylinder, extending longitudinally thereof, the latter exhaust-air passage communicating with the exhaust-passage in the exhaust-handle.

18. In a pneumatic tool, a cylinder, a piston therein, a distribution-valve, a port opened by said piston for permitting exhaust from one side of said valve, a main exhaust-port in alignment with said first-mentioned valve, a handle attached to said cylinder, and having a grasping portion and an exhaust-passage communicating with said ports and leading through said handle.

19. In a pneumatic tool, a cylinder, a piston therein, a distribution-valve, a port opened by said piston for permitting exhaust from one side of said valve, a main exhaust-port in alignment with said first-mentioned valve, a handle attached to said cylinder, and having a grasping portion and an exhaust-passage communicating with said ports leading through said handle in combination with an inlet-handle attached to said cylinder, and means on said inlet-handle for controlling the flow of the motive fluid therethrough.

20. In a pneumatic rammer, a cylinder, a piston therein, and a clamping device within said cylinder adapted to engage said piston and retain the latter when not in use at or near the rear end of said cylinder.

21. In a pneumatic rammer, a cylinder, a piston therein, a recess in said cylinder at or near the rear end thereof, and a split ring located in said recess and adapted to engage said piston.

22. In a pneumatic rammer, the combination of a cylinder, having a recess in the bore thereof, and a split ring in said recess.

23. In a pneumatic rammer, a cylinder, a piston therein, means for controlling the movements of said piston, projections extending from said cylinder at an angle to the axis thereof and grasping handles extending rearwardly at an angle to said projections.

24. In a pneumatic rammer, a cylinder, projections therefrom having passages therein for the inlet and exhaust of the motive fluid

respectively, and handles extending rearwardly from said projections on a line substantially parallel with the axis of said cylinder.

- 5 25. In a pneumatic rammer, a cylinder, projections therefrom having passages therein for the inlet and exhaust of the motive fluid respectively, and handles extending rearwardly from said projections on a line substantially parallel with the axis of said cylinder, one of said handles having an inlet-passage for the motive fluid and a thumb-actuated controlling device for said motive fluid.
- 15 26. In a pneumatic rammer, a cylinder, a distribution-valve therefor, means for effecting the movement of said valve, and an auxiliary port open to live motive fluid after the movement of said valve has been initially effected, whereby an additional supply of live motive fluid is admitted to said valve to retain the latter in the desired position.

25 27. In a pneumatic tool, a cylinder, a differential distribution-valve therein, a port in said cylinder adapted to be uncovered by the piston, near the end of its rearward stroke, a passage leading therefrom to the large area of said valve, a port 37, passage 38 and port 34 in said cylinder, an exhaust-port 36 adapted to communicate with said port 34, by a groove in said valve and an auxiliary port open to live motive fluid after the initial movement of said valve has been effected, whereby an additional supply of live motive fluid is admitted to retain said valve in the desired position.

35 28. In a pneumatic tool, a cylinder, a piston therein, a distribution-valve therefor, an inlet-port 41 in said cylinder controlled by said valve, exhaust-ports 40 and 46 leading therefrom to a main exhaust, a port 34, passage 38 and port 37, whereby motive fluid is admitted to and exhausted from the forward end of said cylinder, ports 30 and 43, a passage 31 in communication therewith and a

passage 32 leading from said passage 31 to the larger area of said distribution-valve, whereby the intermittent movement of the latter is effected, the smaller area of said distribution-valve being located in the rear portion of the valve-box therefor.

29. In a pneumatic tool, a cylinder, a piston therein, a distribution-valve therefor, an inlet-port 41 in said cylinder controlled by said valve, exhaust-ports 40 and 46 leading therefrom to a main exhaust, a port 34, passage 38 and port 37, whereby motive fluid is admitted to and exhausted from the forward end of said cylinder, ports 30 and 43, a passage 31 in communication therewith, a passage 32 leading from said passage 31 to the larger area of said distribution-valve, whereby the intermittent movement of the latter is effected, the smaller area of said distribution-valve being located in the rear portion of the valve-box therefor, and an auxiliary port open to live motive fluid after the movement of said valve has been initially effected, whereby an additional supply of said live motive fluid is admitted to said valve to retain the latter in the desired position.

30. In a pneumatic rammer, a cylinder, a distribution-valve therefor, said valve having differential pressure areas, means for directing constant live-fluid pressure upon the smaller of said pressure areas, means for intermittently admitting pressure to the larger area of said valve and an auxiliary port open to live motive fluid after the movement of said valve has been initially effected by said intermittent pressure, whereby an auxiliary supply of live motive fluid is admitted to said valve to retain the latter in the desired position.
